UNITED STATES PATENT OFFICE.

GEORGE E. BANGHART, OF OLNEY, ILLINOIS.

HAND-EMBROIDERY NEEDLE.

Application filed January 26, 1922. Serial No. 531,881.

To all whom it may concern:

Be it known that I, GEORGE E. BANGHART, a citizen of the United States, residing at Olney, in the county of Richland and State of Illinois, have invented certain new and useful Improvements in Hand-Embroidery Needles, of which the following is a specification.

The invention has for an object to effect improvements in art work hand operated needles, such as are used for tufting, and embroidery, and aims to simplify the construction and functioning of such a device, whereby the manufacture, manipulation of the device in use, and its operative functions will be improved. It is a particular aim to provide an improved guard by which the depth of insertion of the needle is limited, to the end that quick adjustment of the device may be made and fine graduation of tufting secured. It is a most important object of the invention to provide a satisfactory means whereby regularity of the tufting may be secured, and the liability of irregular feed of thread obviated. In this connection, it is an aim of the invention to provide an improved tension device for such use adapted to limit movement of the yarn properly. It is also a further aim of the invention to enable the use of various sizes of yarn satisfactorily, with the same device. A further important aim of the invention is to provide a construction of needle in which the thread will be liable in a minimum degree to become entangled in the fingers of the operator, means being provided whereby it may readily pass longitudinally through the body of the needle device. A further important aim is to provide means whereby needles of different sizes may be interchangeably mounted in the device, so that, in conjunction with the tension of the device, extremely small yarn may be used with the device, as well as large yarn.

Additional objects, advantages and features of invention reside in the construction, arrangement and combination of parts, as will be readily understood from the description following herein, and from the drawings accompanying, wherein,

Figure 1 is a side view of a hand operated tufting needle, constructed in accordance with my invention,

Fig. 2 is a similar view at right angles to Fig. 1,

Fig. 3 is an end view with the arm 15 in section,

Fig. 4 is a fragmentary longitudinal sectional view of the needle mounting, and tension device,

Fig. 5 is longitudinal sectional view of a modified form of barrel and tension device.

There is illustrated a needle device comprising a handle body 10, which may be formed from sheet metal, having a groove 11 formed in one side thereof, the barrel 10 being ordinarily formed in any customary manner. Upon the barrel there is slidable a sleeve 12, split and having ears 13 formed at one side arranged to be drawn together by a clamp screw 14 whereby the sleeve may be tightened upon the barrel to hold it in adjusted position. From the sleeve there is extended outwardly an arm 15, having at its outer extremity a needle encircling guard of annular form, and of a size to receive a needle therethrough with considerable space around the needle, the guard being of a suitable character to act as a stop against cloth, when a needle is thrust thereinto.

The barrel is reduced at the lower end, as at 17, and has snugly set therein a plug 18 having a socket 19 in the outer end to receive the needle, and provided with a binding screw 20 by which the needle may be secured in the socket. The plug may be soldered or otherwise secured in the reduced end of the tube, and is preferably provided with a shoulder 21 against which the end of the tube may be thrust, to hold the device in proper engaged relation. The plug is formed with a longitudinal channel 22 in one side, inclined inwardly, so that it becomes very much deeper at its upper inner part and rested in the upper part of this channel within the reduced portion of the barrel, there is a tube 23, extended axially through the barrel and having a flared end 24 at the upper end. The lower end of the tube is curved so as to aline with the channel 22 where it rests therein. A rib 25 is formed around the outer end of the plug 18, through which the channel 22 extends. The opposite outer end of the barrel is formed with an inturned annular flange 26, at right angles to the axis of the barrel, and having a central large opening therethrough, while the tube 23 is flared so that its edge portion may rest against the flange 26, to which it may be secured by solder or otherwise, as found desirable. The lower end

of the tube 23 will be retained in the channel 22 without special securement at that part, ordinarily. Upon the plug 18, or the lower end of the barrel adjacent the plug, 5 a small boxing 27 is provided, directly over the channel 22 and open at the lower part in line with the channel. In this boxing there is pivoted a lever 28, of the first order, having a lower arm formed with a friction head 10 29 conforming to the shape of the channel 22 in cross section, and adapted to rest upon a yarn laid in the channel and fed therethrough. The opposite end of the lever 28 lies within the boxing 27, and is borne outwardly by a helical spring 30, seated against the lower reduced end of the barrel 10. The lower end of the lever is caused by the spring to bear inwardly into the channel 22. An adjusting screw 31 is engaged in the 15 boxing so as to bear upon the lever directly opposite the spring 30 and in opposition thereto, and by adjustment of this screw, the pressure exerted by the head 29 upon a yarn is limited, as may be found desirable. 20 A needle 32 is removably mounted in the socket 19, having a grooved side aligned with the channel 22.

This construction permits the use of ordinary sewing machine needles for very fine 30 yarns, and for larger yarns, sheet metal needles attached to shanks may be substituted, if desired.

Various details of the structure may be modified, within the intent of the invention 35 as found desirable, it being possible to form a spring arm 33 as a continuation of the le-

ver 28 (as shown in Fig. 5). And to avoid necessity for a groove the barrel 10' may be formed with an outwardly bevelled or channelled part 34 at the lower end, immediately 40 adjacent the plug 18' and the lower end of the tube 23' may be set therein, thus locating it outwardly of the plug 18, the construction of the parts being otherwise the same as before described, except that the 45 tube 23' does not require to be curved.

It will be seen that a simple device is provided adapted to be produced readily in an attractive form, which may be readily operated in the manner usual in the class of 50 work for which the device is adapted. It may be produced at a low cost and the friction device 29 will obviate the pulling back of loops by the resilient action of the yarn, which often occurs in ordinary devices, with 55 very irregular effect, some of the loops being caused to become much shorter than others, and occasional loops being formed quite long.

What is claimed:—

A device of the character described comprising a barrel, a needle mounting plug engaged in one end thereof, a tube having a flared end exposed through the upper end of the barrel, and eccentrically opening 65 through the lower end of the device, and a friction device to engage a yarn passing from the last named end of the tube to a needle in said plug.

In testimony whereof I have affixed my 70 signature.

GEORGE E. BANGHART.
